(57) **CLAIM**

The ornamental design for a teddy-bear-shaped toothbrush, as shown and described.

DESCRIPTION

FIG. 1 is a perspective view of a teddy-bear-shaped toothbrush in accordance with the present invention;

FIG. 2 is a close up view of the head as shown in FIG. 1;

FIG. 3 is a top view thereof;

FIG. 4 is a close up view of the head as shown in FIG. 3;

FIG. 5 is a first side view thereof;

FIG. 6 is a close up view of the head as shown in FIG. 5;

FIG. 7 is a second side view thereof;

FIG. 8 is a close up view of the head as shown in FIG. 7;

FIG. 9 is an enlarged bristle-end view thereof;

FIG. 10 is an enlarged head-end view thereof; and,

FIG. 11 is a bottom view thereof.

The features shown in broken lines in FIGS. 3 and 4 illustrate portions of the teddy-bear-shaped toothbrush that form no part of the claimed design.
